Primary Examiner — Sheryl Lane*Assistant Examiner* — Samantha N Wood(74) Attorney, Agent, or Firm — Raj Abhyanker, P.C.(57) CLAIM

The ornamental design for an aromatherapy diffuser, as shown and described.

DESCRIPTION

FIG. 1 is a top front perspective view for an aromatherapy diffuser showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing portions of the aromatherapy diffuser are included for the purpose of illustrating the environmental structure and forms no part of the claimed design.
